UNITED STATES PATENT OFFICE.

OSCAR REINHOLD, OF DOWNS GROVE, ILLINOIS, ASSIGNOR TO CHURCHILL CABINET COMPANY, OF CHICAGO, ILLINOIS, A CORPORATION OF ILLINOIS.

DESIGN FOR A RADIOCABINET.

Application filed May 4, 1927. Serial No. 21,855. Term of patent 3½ years.

To all whom it may concern:

Be it known that I, OSCAR REINHOLD, a citizen of the United States, residing at Downers Grove, in the county of Du Page and State of Illinois, have invented a new, original, and ornamental Design for Radiocabinets, of which the following is a specification, reference being had to the accompanying drawing, forming part thereof.

The figure is a perspective view of my new cabinet.

I claim:

The ornamental design for a radiocabinet as shown.

In witness that I claim the foregoing as my invention, I have hereunto affixed my signature, this 25 day of April, 1927.

OSCAR REINHOLD.
